UNITED STATES PATENT OFFICE.

WILLIAM HORACE SHERMAN, OF KOKOMO, INDIANA.

HEATING ELEMENT.

Application filed October 29, 1921. Serial No. 511,398.

To all whom it may concern:

Be it known that I, WILLIAM H. SHERMAN, a citizen of the United States, residing at Kokomo, in the county of Howard 5 and State of Indiana, have invented certain new and useful Improvements in Heating Elements, of which the following is a specification.

This invention relates to heating elements 10 and is designed primarily for heating portable hot water boilers or radiators, such as are used for heating the rooms of a building, although it will be understood that the heating element may be used for various 15 purposes.

One feature of the invention is the provision of a burner so constructed that a perfect combustion will be produced, parts of the burner being arranged for automatically 20 determining or regulating the amount of vapor and combustion at different points on the burner.

A further feature of the invention is in so 25 constructing parts of the burner that a vacuum will be created for controlling and maintaining the blaze directly over the center of the burner and for consuming and eliminating odors from the fuel.

A further feature of the invention is in so 30 constructing parts of the burner as to provide a groove or channel in which the liquor fuel is vaporized.

A further feature of the invention is the provision of a fuel conveying duct or pipe 35 for conveying the fuel from a point exteriorly of the burner chamber into the burner, the receiving end of the duct being sufficiently removed from the flame from the burner to avoid possibility of ignition 40 of the fuel at the point of entrance into the duct.

A further feature of the invention is the provision of a fuel tank or container which 45 is so arranged that the heat from the heating element will maintain the fuel within the tank in a warm, or more or less heated condition whereby it will more readily discharge from the tank.

A further feature of the invention is the 50 provision of an automatic float controlled means for feeding the fuel from the tank into the open end of the fuel duct or pipe, said feeding element being so constructed that the fuel will be fed in the form of drops 55 or at a very slow rate, the controlling means for the feeding of the fuel also being ar-

ranged for loosening and preventing undue collection of sediment in parts of the feeding device.

A further feature of the invention is the 60 provision in connection with the fuel duct of a priming cup so that a liquid other than the fuel normally provided for operating the burner may be introduced into the vaporizing chamber and ignited for pre-heating the burner and causing the fuel to vaporize as it enters the burner.

And a further feature of the invention is the provision of means for mounting the burner in a casing so that said burner, together with the fuel duct and priming cup, 70 may be removed as a unit from its casing when desired.

Other objects and advantages will be hereinafter more fully set forth and pointed 75 out in the accompanying specification.

In the accompanying drawings, which are made a part of this application,

Figure 1 is a vertical central sectional view of the heating element showing the 80 same applied to use in connection with a portable hot water heater or radiator,

Figure 2 is a top plan view of the burner with the radiator removed on line 2-2 of Fig. 1, and

Figure 3 is a top plan view of the heating unit showing the fuel tank in position thereon.

Referring to the drawings, 1 indicates a radiator or boiler which may be constructed 90 in any suitable manner and is designed to contain water, said radiator being preferably mounted upon the upper end of a housing or chamber 2, the lower end of the housing or chamber resting upon a movable platform 3, and for convenience of transporting the radiator from place to place the platform is preferably mounted upon a plurality of castors 4.

In order to properly heat the contents of 100 the radiator 1, a burner 5 is located in the housing 2 centrally below the radiator 1, and is mounted on a stem 6 which is in turn secured to a pan 7 removably mounted upon the platform 3, the pan being provided to catch any fuel that might accidentally overflow from the burner. The burner 5 consists of a frame or spider 8 which is attached to and supported by the stem 6, said frame having a circular groove 110 or channel 9 formed in the upper face thereof which acts as a vaporizing chamber when

fuel is entered therein. The vaporized fuel arising from the groove 9 travels between circular drums or shields 10 and 11, the drum 10 resting at the inner edge of the groove 9, while the drum 11 rests at the outer edge of said groove, thereby providing a space between the drums equal in width to the width of the groove. The drums 10 and 11 are each provided with a plurality of perforations 12 and 13, respectively, which extend from the top to the bottom of the drums and form openings for the passage of oxygen and constitute primary burner openings as the fuel will ignite as it passes by said openings, thereby producing a plurality of flame jets on the outer face of the drum 10 and the inner face of the drum 11.

In order to cause the vaporized fuel to properly ignite, oxygen is commingled therewith and in order to properly confine the oxygen and cause it to properly commingle with the vaporized fuel, cones 14 and 15 are associated with the drums 10 and 11, the cone 14 being inverted and supported on the upper end of the stem 6 and positioned interiorly of the drum 10, while the cone 15 is positioned exteriorly of the drum 11 and rests upon brackets 16 attached to the frame 8, these cones forming air passages respectively within the drum 10, and exteriorly of the drum 11. By arranging the cones 14 and 15 as shown, the air passages are gradually restricted from the lower to the upper ends of the drums 10 and 11. This is done in view of the fact that the vapor decreases towards the upper ends of the drums 10 and 11, consequently it is necessary to decrease the supply of oxygen, thereby maintaining substantially uniform flame jets from the bottom to the top of the drums. In order to form a more complete combustion, and at the same time trim the flame from the burner, the upper ends of the cones 14 and 15 are provided with flanges 17 and 18 respectively, which project over the upper ends of the drums 10 and 11 and are slightly spaced therefrom to form narrow passages 19 and 20 respectively, between the flanges and the upper ends of the drums, these restricted passages causing a more perfect combustion and serving to control and prevent the spreading of the flame as it passes between the upper ends of the cones.

The cone 14 is preferably adjustable vertically, as by means of threads on the stem 6 to coact with threads on the frame 8, and a lock-nut 6' serves to prevent accidental movement.

In order to more properly control the flame as it arises from the burner and cause the same to collect centrally over the burner, the cone 14 is provided with a cavity 21 which creates a vacuum and results in drawing the flame towards the center of the

burner, and any fumes that might arise from the fuel will be drawn into the cavity, or into the more intense heat where it will be fully consumed, consequently the burner is practically odorless.

As it is necessary as a matter of necessity to convey the fuel from a source removed from the burner, a duct or pipe 22 is connected with the frame 8 in such manner as to convey fuel into the groove 9, said duct 75 extending through a section 23 of the wall forming the housing 2, and is provided at its outer end with a drip cup 24 into which the fuel is entered for passage through the duct. The fuel is confined in a tank 25 and as it is very desirable to retain the fuel in a warm or heated condition, the tank 25 is preferably constructed in the shape of a ring and is located around the periphery of the radiator 1, brackets 26 or other suitable supporting means being provided for the tank, and said tank may be slightly spaced from the walls of the radiator or placed in close proximity thereto, as may be desired, consequently when the contents of the radiator 1 becomes heated, such heat will be imparted to the contents of the tank thereby causing the fluid therein to flow readily at all times.

In burners of this class it is necessary to provide an absolutely uniform feed for the fuel and such that the fuel will be very slowly and constantly fed, and to this end a fuel chamber 27 is connected to a cap 28, said cap having a neck 29 which is threaded into a collar 30 depending from the tank 25, the upper end of the neck extending a short distance into the tank. The fuel chamber 27 has an upwardly extending flange 31 which projects a distance above the normal fuel level in the fuel chamber while the meeting edges of the fuel chamber 27 and the cap 28 are provided with shoulders 32 and 33 respectively, between which is introduced a packing 34 thereby sealing the fuel chamber against leakage.

Mounted within the fuel chamber 27 is a float 35 through which extends a stem 36, the upper end of the stem forming a valve 37 which enters a fuel passage 38 in the neck 29, the valve 37 being preferably tapered and engaging with a tapered seat when the valve is in closed position and which regulates the admission or feed of the fuel into the fuel chamber. The lower end of the stem 36 fits loosely in a bore 39 in a valve sleeve 40, said valve sleeve extending through an extension 41 depending from the fuel chamber 27. The lower end of the bore 39 terminates in ports 42 which are preferably diametrically opposite each other and extend through the tapered end 43 of the sleeve 40, the end of the sleeve terminating in a finger or dropping point 44, and by arranging the sleeve in this manner the fuel will pass about the lower part of stem 36 120

to the bottom of the sleeve and will be discharged into the drip cup in the form of drops. Threaded onto the extension 41 is a regulating nut 45 which is so constructed 5 that it will control the feed of the fuel through the ports 42 and will regulate the number of drops discharged from the end of the finger 44 in a prescribed length of time; or said nut may be operated to entirely cut off the flow of fuel through the ports. After the nut has been properly adjusted to regulate the flow of fuel an adjustable stop 46 is clamped around the nut, said stop, when the nut is moved to open position, striking a lug 47 on the bottom of the fuel chamber, thereby preventing the nut from being opened to a greater extent, consequently when the nut has been closed to shut off the fuel and it is desired to again 20 operate the burner, it is but necessary to rotate the nut until the stop engages the lug 47. If a greater amount of fuel is to be used the stop 46 is loosened from the nut and the nut turned to feed a greater amount of 25 fuel after which the stop is again clamped onto the nut and by this arrangement the same amount of fuel will be fed when the nut is moved from closed to open position without requiring any further adjustment 30 or regulation. The portion of the stem 36 entering the sleeve 40 not only serves, in conjunction with the valve 37, to hold the float 35 in proper position, but also serves to agitate the oil in the valve sleeve by suction 35 and compression, thus causing any oil clot to break loose from the walls of the bore in the sleeve, or that may collect adjacent or in the ports 42, thus maintaining a more constant feed of the fuel through the ports. 40 The neck 29 has a vent opening 48 for ventilating the interior of the fuel chamber, a tube 49 extending upwardly from the end of the neck 29 to a point adjacent the upper wall of the tank so that fuel cannot 45 feed through the vent opening. A strainer tube 50 is extended vertically through the tank 25, and if desired a gauze strainer 51 may be placed around the strainer tube for removing sediment and the like from the 50 liquid fuel. If desired a cap 52 may be extended through the wall of the tank 25 and over the end of the strainer tube 50 thereby giving access to the interior of the tank for 55 the introduction or removal of the strainer tube and gauze. The tank 25 is also provided with a neck 53 which forms a filler opening for the tank, a cap 54 being threaded over the end of the neck and preferably provided with a vent opening 55 to prevent 60 a vacuum forming in the tank. 35 As it is necessary to heat the parts of the burner sufficiently so that the liquid fuel will be vaporized as it enters the groove 9 of the burner, it is necessary to first introduce a quantity of highly inflammable material

into the vaporizing groove prior to admitting the natural fuel, and to this end a priming cup 56 is connected with the duct 22 at a point adjacent its connection with the burner, the cup being of a size to hold the 70 proper amount of highly inflammable substance to properly heat the burner, and in order to prevent the inflammable substance entering the duct until such time as a prescribed amount of the inflammable material 75 has been entered in the priming cup, a valve 57 is provided which closes the passage through the lower end of the priming cup until such time as it is desired to admit the inflammable material into the vaporizing 80 groove of the burner.

In applying the burner to use the section 23 is moved outwardly and as the pan 7 is connected to said section the burner and fuel duct 22 are moved outwardly with the pan, these parts being connected together to form 85 a unit. As soon as the priming cup has been filled with highly inflammable material the valve 57 is opened to admit the inflammable material to the vaporizing groove 9, 90 when said inflammable material is ignited and the section 23 then returned to closed position such action returning the burner 5 to its initial position and again centering the drip cup 24 below the drip finger 44. As 95 soon as the highly inflammable material has been burning a sufficient length of time to cause the fuel to vaporize on reaching the heated parts of the burner, the nut 45 is operated to open the ports 42 when the fuel 100 from the tank 25 will begin to feed into the drip cup 24 and from thence through the duct 22 into the vaporizing groove and the surrounding parts of the burner. This fuel 105 will be instantly vaporized on reaching the heated channel 9 and will ignite and continue to burn so long as the fuel is fed into the vaporizing chamber.

Should, for any reason, the fuel openings 110 controlled by the float become foul, or in fact any parts thereof, they may be readily cleansed by unscrewing the fuel chamber from the cap 28 and the parts of the device separated and cleansed, and likewise should the strainer tube and gauze become filled 115 with sediment or the like they may be easily removed and cleansed.

Having thus fully described my said invention, what I claim as new and desire to 120 secure by Letters Patent, is:

1. In a heating element, a frame structure having a vaporizing groove therein, means comprising a pair of perforated concentrically arranged cylinders extending upwardly from the same groove for confining the vaporized fuel and permitting air to enter in jets between the said cylinders, and a cone extending around the outer cylinder and arranged to conduct air to the 125 perforations of the said outer cylinder in 130

- decreasing quantities from the bottom of the cylinder to the top thereof said cone having a flange spaced above and overhanging the outer cylinder, substantially as set forth.
5. 2. In a heating element, a frame structure having a vaporizing groove therein, means comprising a pair of perforated concentrically arranged cylinders extending upwardly from the same groove for confining the vaporized fuel and permitting air to enter in jets between the said cylinders, a cone extending around the outer cylinder and arranged to conduct air to the perforations of the said outer cylinder in decreasing quantities from the bottom of the cylinder to the top thereof, said cone having a flange spaced above and overhanging the outer cylinder, and a second cone within the inner cylinder and having a flange spaced above and overhanging the inner cylinder, said second cone arranged to conduct air to the perforations of said inner cylinder in quantities decreasing from the bottom to the top thereof and said second cone being closed at the bottom whereby the fumes from the burner are caused to be drawn inwardly, substantially as set forth. 70
10. 15. 20. 25. 30. 35. 40. 45. 50. 55. 60. 65. 70. 75. 80. 85. 90. 95. 100. 105. 110. 115. 120. 125. 130.
3. In a heating element, a frame structure having a vaporizing groove therein, means comprising a pair of perforated concentrically arranged cylinders extending upwardly from the same groove for confining the vaporized fuel and permitting air to enter in jets between the said cylinders, a cone extending around the outer cylinder and arranged to conduct air to the perforations of the said outer cylinder in decreasing quantities from the bottom of the cylinder to the top thereof, said cone having a flange spaced above and overhanging the outer cylinder, and a second cone within the inner cylinder and having a flange spaced above and overhanging the inner cylinder the flanges of said cones lying substantially in the same horizontal plane, said second cone being closed at the bottom whereby fumes from the burner are caused to be drawn inwardly, substantially as set forth. 95
4. In a heating element, a frame structure comprising an annular combustion passage defined by a pair of perforated concentrically arranged cylinders, a cone arranged within the inner cylinder provided with a horizontal flange spaced above and overhanging the inner cylinder said cone extending downwardly from said flange to a point adjacent the plane of the bottoms of the cylinders and said cone being closed at the bottom and open at the top whereby fumes from the burner will be drawn inwardly, substantially as set forth. 100
5. In a heating element, a frame structure having a vaporizing groove therein, means comprising a pair of perforated concentrically arranged cylinders extending upwardly from the same groove for confining the vaporized fuel and permitting air to enter in jets between the said cylinders, a cone extending around the outer cylinder and arranged to conduct air to the perforations of the said outer cylinder in decreasing quantities from the bottom of the cylinder to the top thereof said cone having a flange spaced above and overhanging the outer cylinder, and a second cone within the inner cylinder and having a flange spaced above and overhanging the inner cylinder, said second cone arranged to conduct air to the perforations of said inner cylinder in quantities decreasing from the bottom to the top thereof and said second cone being closed at the bottom whereby the fumes from the burner are caused to be drawn inwardly, substantially as set forth. 105
6. In a heating element, a housing having a removable section, a pan secured to said section, a burner carried by the pan, fuel-supplying means for the burner including a tube mounted in said removable section and leading to the burner, a priming device on the tube inside the housing, a drip cup at the outer end of the tube, and an annular fuel tank encircling the heating element said tank having means to feed liquid fuel in drops to the drip cup, substantially as set forth. 110
7. In a heating element, a frame structure having a vaporizing groove therein, means comprising a pair of perforated concentrically arranged cylinders extending upwardly from the said groove for confining the vaporized fuel and causing the air to enter in jets between the said cylinders, and an inverted cone arranged within the inner cylinder provided with a horizontal flange at its upper end overhanging the inner cylinder but spaced from the upper margin thereof, substantially as set forth. 115
8. In a heating element, a frame structure having a vaporizing groove therein, means comprising a pair of perforated concentrically arranged cylinders extending upwardly from the said groove for confining the vaporized fuel and causing the air to enter in jets between the said cylinders, and an inverted cone arranged within the inner cylinder the apex of said cone being near the level of the vaporizing groove and the base approximately on a level with the upper ends of said cylinders, substantially as set forth. 120
9. A burner comprising a main member, perforated tubular inner and outer casings having their lower ends resting directly on the main member, the main member being provided with an annular fuel trough located between the casings, means for discharging fuel into the trough, a cap supported on the main member and located outwardly of the outer casing, the cap slanting inwardly from its lower end to its upper end, the main member having an air inlet opening discharging between the cap and 125

the outer casing; a core located within the inner casing and slanting outwardly from its lower end to its upper end, the main member having an air inlet opening disposed 5 between the core and the inner casing; and means for supporting the core from the main member, independently of the casing.

10. A burner comprising a main member; a support vertically adjustable in the main member; means for holding the support in adjusted positions; an inverted conical core carried by the upper end of the support, a conical cap mounted on the main member,

spaced perforated annular casings mounted on the main member and located between 15 the core and the cap, and means for discharging fuel between the casings.

In witness whereof, I have hereunto set my hand and seal at Kokomo, Indiana, this 21st day of October, A. D. nineteen hundred 20 and twenty-one.
